DESIGN FOR A TAXICAB

Lynn Brodton, New York, N. Y.

Application September 4, 1947, Serial No. 141,206

Term of patent 14 years

(Cl. D14—3)

To all whom it may concern:

Be it known that I, Lynn Brodton, a citizen of the United States, residing at city of New York, county of New York, and State of New York, have invented a new, original, and ornamental Design for Taxicab, of which the following is a specification, reference being had to the accompanying drawing, forming a part thereof, wherein:

Fig. 1 is a perspective view looking from the front to the rear of the taxicab of my design; and

Fig. 2 is a perspective view looking from the rear to the front of the taxicab.

The characteristic features of my design reside in the portions shown by means of full lines in the drawing.

I claim:

The ornamental design for a taxicab, substantially as shown and described.

LYNN BRODTON.
